UNITED STATES PATENT OFFICE.

WILLIAM THOMAS CREED, OF IRVING, TEXAS.

SHOE-HEEL HOLDER.

1,390,886.

Specification of Letters Patent. Patented Sept. 13, 1921.

Application filed February 27, 1920. Serial No. 361,791.

To all whom it may concern:

Be it known that I, WILLIAM T. CREED, a citizen of the United States, residing at Irving, in the county of Dallas and State of Texas, have invented new and useful Improvements in Shoe-Heel Holders, of which the following is a specification.

This invention relates to improvements in shoe making devices and has for an object the provision of means for removably holding a heel in position for attachment to a shoe and is especially designed for use in connection with the so called French, or other high heels.

15 An object of the invention is the provision of a holder, which is carried by a shoe last and shaped so as to receive the heel and hold it in position, to facilitate the attachment of the heel to a shoe.

20 Another object is the provision of means for clamping the heel within the holder, so as to hold it against accidental displacement during the operation of securing it to the shoe, the clamp being so constructed as to permit of the ready positioning and removal of the heel within and from the holder.

With the above and other objects in view, the invention further consists of the following novel features and details of construction, to be hereinafter more fully described and illustrated in the accompanying drawings.

In the drawings:

35 Figure 1 is a side elevation of a shoe last equipped with the improved heel holder.

Fig. 2 is a vertical longitudinal sectional view of the same.

Fig. 3 is a horizontal section.

40 Fig. 4 is a perspective view of the last with the heel removed.

Fig. 5 is a detail perspective view of the clamp showing the parts in separated relation.

45 Referring to the drawings in detail where-in like characters of reference denote corresponding parts, the invention comprises a shoe last which is indicated by the reference character 10. This last may be removably

50 mounted upon a standard, the former having formed therein a socket 12, which removably receives the upper end of the standard 11 as is usual in devices of this character. The invention resides in the provision of a heel holder and for this purpose,

the last 10 is provided at its heel end with a vertically projecting extension 13, the latter being concaved as shown at 14 to conform to the curvature of the shoe heel and being provided with a curved recess 15 at the bottom thereof to receive the lower projecting lift of the heel.

The heel, which is indicated at 16 is placed within the holder 13 and is held against accidental displacement through the medium of a removable clamp 17. This clamp comprises a substantially U-shaped member 18, having one end provided with a laterally extending tongue 19 and its opposite end provided with a laterally inwardly extending tongue 20, the extremity 21 of which is enlarged as shown. The tongue 19 is adapted to be removably positioned within an opening 22 formed in one end of a connecting bar 23, the opposite end of this bar being provided with laterally extending spaced projections 24, which are adapted to be positioned upon opposite sides of the tongue 20 between the extremity 21 and the adjacent end of the member 18. This provides means for quickly attaching, or removing the bar 23 from the member 18, when the heel is being secured within or removed from the holder 13.

In order to tightly clamp the heel in position, the member 18 is thickened intermediate its ends as shown at 25 and this thickened portion is provided with a threaded opening 26 for the reception of a screw 27, which is adapted to pass through the opening 26 and bear against the rear of the extension 13. The outer end of the screw is provided with a knurled head 28 to provide convenient means for operation.

It is believed from the foregoing description and the accompanying drawings, that the operation, construction and the advantages of the invention will be apparent, and the right is reserved to make such changes in its form, proportions and minor details of construction as properly fall within the scope of the appended claim.

Having described the invention what is claimed is:—

In combination with a shoe last, a vertically disposed concaved member extending from one end of said shoe last and provided with a curved recess, a substantially U-shaped member engaging said extension and having a threaded opening therein, a con-

necting bar provided with laterally extending spaced projections and having an opening formed therein, a tongue extending laterally from one end of said U-shaped member and adapted to engage the opening in said connecting bar, an enlarged tongue extending laterally from the opposite end

of said U-shaped member and adapted to engage the spaced projections of said bar, a screw engaging the threaded opening in 10 said U-shaped member and a knurled head secured to the outer end of said screw.

In testimony whereof I affix my signature.
WILLIAM THOMAS CREED.
